TRANSPORTATION CONTAINER

Clarence H. Williamson, Cleveland, Ohio, assignor to The Youngstown Steel Door Company, Cleveland, Ohio, a corporation of Ohio

Application March 31, 1932, Serial No. 602,146

20 Claims. (Cl. 189—46)

This invention relates to improvements in transportation containers and more particularly doors therefor.

One object of the invention is to provide a door arrangement for transportation containers of the railway type wherein the construction consists of the minimum number of parts relatively inexpensive to manufacture and assemble.

Another object of the invention is to provide 10 a door construction particularly adapted for transportation containers wherein all the fixtures for hingedly mounting the doors, latching the same, and to provide shrouds for certain parts of the locking mechanism, are consolidated 15 into two preferably cast units.

Still another object of the invention is to provide a door construction of the type indicated in the preceding paragraph wherein provision is made for ventilating the interior of the container to eliminate sweating.

A further object of the invention is to provide 20 a transportation container having doors with sealing means in the door joints wherein provision is made for ventilating the interior of the container through the doors without danger of admission of rain or other foreign matter to the interior of the container.

Still another object of the invention is to provide 25 a container and door construction in accordance with all of the preceding objects of invention wherein the arrangements may be incorporated in either a two door arrangement or a double door of the folding leaf type arrangement.

Other objects of the invention will more clearly appear from the description and claims hereinafter following considered in connection with the drawings and forming a part hereof.

In said drawings, Figure 1 is an end elevational view of a railway type of container showing the improvements incorporated therein, parts being broken away in order to better accommodate the view on the sheet. Figure 2 is a part horizontal, sectional view, part top plan view of the top edges 45 of the doors when in closed position, parts being broken away at one end to accommodate the view on the sheet. Figure 3 is a horizontal sectional view, corresponding to the line 3—3 of Figure 1. Figure 4 is an enlarged detailed horizontal sectional view, corresponding to the line 4—4 of Figure 1. Figure 5 is a view similar to Figure 4, corresponding to the line 5—5 of Figure 1. Figure 6 is an enlarged vertical sectional view, corresponding substantially to the line 55 6—6 of Figure 1, parts being broken away in order to accommodate the view on the sheet. Figure 7 is an enlarged vertical detailed sectional view, corresponding to the section line 7—7 of Figure 1. And Figure 8 is an end elevational view of one end of a door.

In said drawings, a portion of the end sheathing of the container is indicated at 10; the roof sheet at 11, the side posts of the door opening at 12—12, the sill at 13 and the lintel at 14, the latter having an upstanding outer flange 15, horizontal web 16 and inner depending flange 17. Over the door opening and secured to the roof sheet is extended a combined drip and weather-protecting plate 18 sloped along its top edge, as clearly shown in Figure 1, downwardly to each side from the center. The lintel 14 is preferably braced by a reinforcing plate 19 secured along its lower edge to the depending flange 17 and along its upper edge to the roof sheet, as indicated in Figure 6. On the upper flange of 70 the sill 13 is secured an angular threshold plate 20 and a portion of the plank flooring is indicated at 21, there preferably being a floor sheet, 22 beneath the planks, as indicated.

In the particular arrangement chosen for illustration, the door opening of the container is closed by two pivoted doors, each comprising two pivotally connected leaves, the leaves being designated broadly as A—A for the two outermost leaves and B and C for the two inner leaves, it 85 being understood that the two outer leaves A—A are of like construction oppositely arranged, whereas the two leaves B and C differ somewhat in detailed construction at their meeting edges, as hereinafter pointed out.

In carrying out the invention, each door or door leaf, as the case may be, is comprised of five units, that is, an upper casting; a lower casting; two edge reinforcing bars extending between and connected at their ends to the upper and lower 95 castings; and a sheet metal closure panel secured around its edges to the castings and reinforcing bars. A detailed description of one of the door leaves is believed to be sufficient except as additional description may be required for certain 100 detailed differences hereinafter set forth.

Referring to the outer leaf A appearing at the left of Figure 1, the same comprises an upper casting 23, a lower casting 24, two angle side bars or reinforcing elements 25—25 and a sheet 105 metal closure panel 26, the latter preferably having one or more integrally formed reinforcing corrugations 27 therein extended outwardly. Each casting 23 and 24 is provided at that end adjacent the corresponding door post, with a 110 plurality of integrally formed hinge lugs 28—28 to which is pivotally connected a hinge link 29, the latter in turn being pivotally connected to hinge butts 30—30 in turn secured to the door post, this link or articulated type of hinge being 115 employed on account of the door being of the double leaf type. Each of the castings 23—24 is also formed at its opposite end with integral hinge lugs 31—31 to provide pivotal connection 120 with the corresponding upper and lower castings.

32 and 133, respectively, of the adjacent door leaf B, as clearly shown.

Referring to Figures 6 and 7, it will be seen that each of the upper castings 23 and 32 is formed 5 with a box-like section having an outer wall 33, a top wall 34, a bottom wall 35 and an inner wall 36, the wall 36 being continued downwardly and thence slightly outwardly offset, as indicated at 10 37 and ending in a depending flange 38. Each of 15 the upper castings also has its outer wall 33 upwardly extended to provide a weather sealing flange 39 to minimize entrance of rain or other 20 foreign matter into the joint along the upper edges of the doors. Each upper casting of the 25 doors is further provided in the box section thereof, with vent openings 89—89 in the outer wall 33 thereof and near each end and, in the top wall 34 thereof, with a centrally located opening 40, it being observed that the openings 40 are longitudinally offset from the openings 89 so that 30 a broken or interrupted passage is formed for air circulating through said openings. Each of the upper openings 40, when the doors are in closed position, are aligned with corresponding 35 openings 41 in the web section 16 of the lintel and to permit circulation of air to the interior of the car, the lintel reinforcing plate 19 is also provided with vent openings 42. In this manner, as will be evident, notwithstanding that the edges 40 around the doors are sealed with gaskets as hereinafter described, circulation of air between the exterior and interior of the container is permitted through the upper castings of the doors without danger of rain or the like being admitted 45 to the interior of the container.

Each of the lower castings 24 and 133 of the door leaves A and B, respectively, are similar to the upper castings, that is, each is formed with an integral box section having outer wall 43, top wall 44, inner wall 45 and bottom wall 46. The outer wall 43 has a depending flange 47, which functions as a weather seal for the joints along the bottom edges of the door, as best indicated in Figure 6. Each back wall 45 is extended upwardly, as indicated at 48, and is then laterally outwardly offset, as indicated at 49 and terminates in an upper flange 50. The bottom castings likewise are provided with ventilating openings consisting of holes 51—51 in the outer wall 43 and a plurality of openings 52—52 in the inner wall 45, the latter being longitudinally offset from the openings 51, as best indicated in Figure 1, thus providing broken passages for the air and preventing admission of foreign matter 55 to the interior of the container. All bottom castings will be similarly provided with ventilating openings, as will be understood.

Referring again to the upper castings, as best shown in Figures 6 and 7, it will be noted that 60 each is formed in its upper wall with a longitudinally extending depressed groove 53, which serves to collect any moisture that may enter the joint between the tops of the doors and the lintel and such collected moisture will drip down 65 through the openings 40 and is then drained off, on the outer sides of the doors, through drain holes 54—54 formed in the bottom walls 35 of the castings.

Each of the side braces 25 is preferably a 70 rolled angle and is riveted at its ends to the upper and lower castings by both of its flanges as by the rivets 55 and 56. To accommodate the inner flange of each angle, the castings are recessed on their inner faces an amount corresponding to the thickness of the flange, as in-

dicated at 57, and similarly on their outer faces, as indicated at 58, so as to provide a flush arrangement between the angles and the castings. As will be understood, the ends of the angle or side elements 25 are overlapped on the castings 80 a sufficient amount to obtain the necessary attachment. In this connection, it will be observed that, by merely changing the lengths of the side angles 25, the same upper and lower castings 85 may be employed for doors of different height, thus reducing cost of fabrication where doors of different size are required.

The sheet metal panel 26, preferably one piece, has its upper edge lapped under the depending flange of the upper casting, as indicated at 90 59 in Figure 6, and has its lower edge lapped on the outer side of the lower casting, as indicated at 60, so as to form shedding joints and prevent collection of moisture and resultant corrosion. Along the side edges, each sheet metal panel is 95 lapped over and secured to the outer face of the corresponding side angles 25, as by the rivets 61—61.

Referring to the upper and lower castings on the door leaf C, said castings at the free edge 100 of the door leaf are somewhat modified so as to provide flanges 62—62, which are inclined outwardly and backwardly, as best indicated in Figure 5, and the corresponding edge angle 125 has its outer flange 126 correspondingly bent and 105 riveted to the casting flanges 62. The upper and lower castings of the door leaf B are correspondingly modified, as best indicated in Figure 5, each of said castings having an outwardly extending flange 63 and a terminal flange 64 110 at right angles thereto, the flanges 64 being adapted to engage over the edge formations of the door leaf C and consequently, serving to hold the latter in closed position when the door leaf B is closed and latched, as will be clear from 115 Figure 5. The corresponding edge angle 225 of the door leaf B has its flange 226 similarly inclined and riveted to the castings so as to be parallel to the flange 126 of the angle on the door leaf C.

Each of the upper and lower castings of each of the door leaves B and C is further provided at the end pivotally connected to its corresponding main door leaf A, with an integral hook shaped lug 65 extending inwardly as shown in 125 Figures 2, 3 and 4, said hook lugs being adapted to enter through corresponding slots 66 and 67 in the door lintel and threshold plate respectively, when and as the doors are moved to fully closed position, the hooks thus engaging behind 130 the lintel and threshold plate and serving to retain the doors in closed position, as will be understood.

To latch the doors in closed position, the following arrangement is provided. Riveted to the 135 door leaf B, the last to close, is a bearing casting 68 in which is rotatably journaled a plate 69 to which are pivotally connected upper and lower locking bars 70—70. For operating the bars and plates 69, the plate has pivotally connected there- 140 to a hasp handle 71 adapted to take over a staple 72 carried by another casting 73 secured to the door leaf C. Said casting 73 is formed with a slotted housing 74 in which is vertically slidable a pin 75 adapted to be entered through an opening in the staple 72 to thereby lock the hasp in place, as will be understood. A suitable key operated lock with a plunger may also be mounted on the casting 73, the plunger to engage the upper end of the pin 75 so as to prevent tamper- 145 150

ing therewith except by authorized holders of the key for the lock.

As best shown in Figure 6, the upper and lower castings on the door leaf B are formed with vertically aligned guide or bearing openings 76 in the top and bottom walls of each of the box sections for the enlarged ends 77 of the locking bars which, when projected upwardly and downwardly to their maximum extent, enter openings 78 and 79, respectively, in the lintel and sill to hold the doors in closed position, it being thus evident that the castings provide shrouds for the locking bars.

To seal the several joints between the doors and the door framework, between the two leaves of each door and between the meeting edges of the two doors, any suitable yieldable sealing arrangement may be provided, the one shown comprising a special rolled rubber section 80, as best shown in Figures 4 and 5. Each such rubber strip has a relatively thin flat central portion and enlarged rounded cored edges or beads. The rubber strips will be applied to the respective vertical edges of the doors as by clamping plates 81 and rivets 82 and also along the inner faces of the top castings, as indicated at Figure 6, the latter sealing strips cooperating with the lintel flange 17.

From the preceding description, considered in connection with the drawings, it will be observed that between each opposed vertically extending surface of two doors and opposed surfaces of a door and fixed part of the container, a double line of seal is provided by the two beads extending lengthwise of the opposed surfaces and with an intervening air space between the lines of seal. In this manner, the seal is especially effective since, should any foreign matter be able to pass the first line of sealing contact, the intervening air space or pocket will serve to destroy the momentum thereof so that passage beyond the second line of seal is practically impossible.

As apparent from Figure 1, the top and bottom castings on the main or outer door leaves A—A are of considerably greater vertical extent than the castings on the other door leaves B and C, such heavier construction being advisable on account of the greater loads which have to be sustained by the castings on the door leaves A—A, it being obvious that each door leaf A is required to sustain the weight of its corresponding leaf B or C.

From the preceding description, it will be seen that, while the door joints are substantially hermetically sealed by compressible rubber sealing strips, nevertheless ventilation is provided to eliminate or minimize sweating without any danger of injury to the contents of the container from the elements. Further, the use of castings as described, simplifies and reduces the cost of manufacture since all the so-called necessary fixtures for the doors are incorporated in the castings, that is, the hinge lugs, the ventilating openings, the locking flanges for retaining the doors closed, the hook lugs 65 for locking the doors to the door framework; and the shrouds for the locking bars. The sheet metal pane's may be sheared and pressed at minimum expense and the assembling of the same together with the edge reinforcing angles is simplified to an ordinary riveting operation.

The invention in its preferred form as applied to doors of the double leaf type has herein been shown and described in detail but it is obvious

that many of the broad features of the invention may be utilized with equal effectiveness in single leaf type doors and also that certain features of the invention may be employed in door structures for other purposes than transportation containers. All such changes and modifications are contemplated that come within the scope of the claims appended hereto.

What is claimed is:

1. A door of the character described comprising: two hollow end members each having hinge lugs integrally formed thereon at one end and an attaching flange extending therealong; two reinforcing elements extending between the members and secured at their ends thereto and, with the members, forming the frame of the door; and a sheet metal panel secured along its edges to said flanges of said members and elements. 85
2. A door leaf for a hinged two leaf door of the character described comprising: two end members each having hinge lugs integrally formed at each of its ends and an attaching flange extending between the end sets of hinge lugs; two reinforcing bars extending between the members and secured at their ends thereto; and a sheet metal closure panel secured along its edges to said flanges of said members and to the bars. 95
3. A door of the character described comprising: two end members each having hinge lugs integrally formed at one end thereof and an overhanging projecting flange at its other end adapted to overlie and retain the edge of an adjacent door; two reinforcing bars extending between the members and secured at their ends thereto; and a closure sheet metal panel secured along its edges to said bars and members, the panel being underlapped relative to the upper member and overlapped relative to the lower member. 105
4. A member for a pivoted door having integrally formed hinge lugs at one end thereof and a hollow section extending longitudinally thereof, said hollow section having a vent opening in an outer wall and an additional offset vent opening in another wall thereof. 115
5. A member for pivoted doors having integrally formed hinge lugs at each end thereof and an intermediate longitudinally extending hollow section, said hollow section being provided with relatively offset vent openings in two of the walls thereof. 120
6. A member for pivoted doors having integrally formed hinge lugs at one end thereof, an outwardly extending overhanging flange at the other end thereof and an intermediate box section, said lugs extending outwardly beyond the 130 box section and the latter having an integrally formed attaching flange extending lengthwise thereof for a panel sheet.
7. A member for a pivoted door having integrally formed hinge lugs at one end thereof projecting outwardly and an integrally formed hook lug on the inner side thereof projecting inwardly at the end adjacent the hinge lugs. 135
8. A member for a pivoted door having hinge lugs at one end thereof, an outwardly extended overhanging flange at the other end thereof and a hook lug on the inner side thereof adjacent the hinge lugs, said hinge lugs, hook lug and flange being all integrally formed. 140
9. A member for pivoted doors comprising: 145 hinge lugs at one end thereof, a hook lug on the inner side of the casting adjacent the hinge lugs; an outwardly extended overhanging flange at the other end of the member; and an intermediate hollow section formed with relatively offset inner 150

- and outer vent openings, all of said lugs, flange and hollow section being integrally formed.
10. A unitary member for a pivoted door having: hinge lugs at one end thereof and a longitudinally extending hollow section with top and bottom walls all integrally formed, said top and bottom walls at the end of the member remote from the hinge lugs being provided with alined openings providing guides for a vertically disposed locking bar.
11. In a transportation container having a door opening defined in part by a lintel; a pivotally mounted door for said opening, said door including a top casting having a longitudinally extending box section and integrally formed hinge lugs at one end thereof, said box section being provided with a vent opening in the front thereof and a relatively offset vent opening in the top wall thereof, said lintel having a corresponding alined vent opening.
12. In a transportation container having a door opening, a pivoted door for said opening, said door including a bottom member having a longitudinally extending box section and hinge lugs integrally formed at one end thereof, said box section being provided with vent openings in the outer and inner walls thereof, the inner wall opening being horizontally offset with respect to the outer wall opening to thereby provide ventilation for the container while preventing passage of rain through the member.
13. A pivoted door for a transportation container or the like having a door opening, said door being comprised of five units in the form of upper and lower horizontally extending castings having integral hinge lugs at one end thereof, front and rear edge vertically disposed bars extending between and connected to the castings, and a sheet metal panel secured to the castings and bars, the upper edge of the panel being lapped under the upper casting and the lower edge of the panel being lapped over the lower casting.
14. In a transportation container having a door opening, two pivotally mounted doors for closing said opening, each door comprising two leaves pivotally connected and each door leaf comprising upper and lower castings, two edge connecting bars and a sheet metal panel, the castings of the two main door leaves having hinge lugs integrally formed at each end thereof; the castings of each of the inner door leaves having integrally formed hinge lugs at one end thereof for pivotal connection to the corresponding main door leaves, the opposite ends of the castings of the inner door leaves having integral cooperable formations, one adapted to overlie the other for retaining the doors in closed position.
15. In a transportation container having a door opening, two pivotally mounted doors for closing said opening, each door comprising two leaves pivotally connected and each door leaf comprising upper and lower castings, two edge connecting bars and a sheet metal panel, the castings of the two main door leaves having hinge lugs integrally formed at each end thereof, the castings of each of the inner door leaves having integrally formed hinge lugs at one end thereof for pivotal connection to the corresponding main door leaves, the opposite ends of the castings of the inner door leaves having integral cooperable formations, one adapted to overlie the other for retaining the doors in closed position.
16. In a transportation container having a door opening defined in part by side posts and lintel, pivoted doors for closing said opening, sealing means between the doors and said door framing members; and means providing ventilation between the interior and exterior of the container, said means including alined vent openings in the upper parts of the doors and door lintel.
17. In a transportation container having a door opening defined by a sill, side posts and lintel: pivoted doors for closing said opening, each door comprising two leaves pivotally connected; each door leaf comprising upper and lower castings, two connecting bars and a sheet metal panel; the castings of the main end door leaves having integrally formed hinge lugs at each end thereof for pivotal connection to the door frame and inner door leaf; the castings on one inner door leaf having a flanged formation adapted to overlie and retain the castings of the adjacent inner door leaf and provided also with vertically alined guide openings for locking bars; manually operable locking bars on said inner door leaf; the upper and lower castings of each of the inner door leaves having integrally formed hook lugs adapted to enter openings in and engage with the door lintel and sill respectively.
18. A pivoted door including an upper member having integrally formed hinge lugs at one end thereof and a longitudinally extending hollow box section, said box section being provided with relatively staggered air vent openings in two of the walls thereof, the top wall of said box section having a longitudinally extending moisture collecting groove and the bottom wall of said section having drain holes therein.
19. In a transportation container having a door opening and a pivoted door therefor wherein the door has a vertically extending surface opposed to another vertical surface when the door is in closed position, means providing a weather seal between said opposed surfaces, said means including a rubber strip extending lengthwise of and secured to one of said surfaces, said strip being provided with integrally formed, outstanding beads along its edges with an intervening relatively thin inset securing section whereby, when the door is closed, two spaced lines of sealing contact are provided along the crests of said beads, and means located between the beads disposed below the crests thereof for securing the strip to the door.
20. As an article of manufacture, a horizontal edge member for a pivoted door, said member having a main horizontally extending hollow section provided at each end thereof with a set of vertically extending faces disposed at right angles to each other, whereby a bar having an angle section may be secured thereto, said hollow main section having a longitudinally extending attaching flange along one edge thereof and, at one end, being provided with outwardly projecting hinge lugs, said hollow section, lugs and flange being integrally formed.

CLARENCE H. WILLIAMSON.
